UNITED STATES PATENT OFFICE.

CARL HITZL, OF CHICAGO, ILLINOIS.

DESIGN FOR A BOTTLE.

No. 37,641.

Specification for Design.

Patented Nov. 7, 1905.

Application filed August 28, 1905. Serial No. 276,167. Term of patent 14 years.

To all whom it may concern:

Be it known that I, CARL HITZL, a citizen of the United States, residing at Chicago, in the county of Cook and State of Illinois, have invented a new, original, and ornamental Design for a Bottle, of which the following is a specification, reference being had to the accompanying drawings, forming a part hereof.

Figure 1 is a view in elevation of a bottle, showing my new design; Fig. 2, a similar view of the same, but taken at an angle to the view presented in Fig. 1; and Fig. 3 a plan view of the bottle.

I claim—

The ornamental design for a bottle, as shown.

CARL HITZL.
